C. F. LORENZ

LUMINOUS ELECTRODE DISCHARGE LAMP

Filed March 14, 1923

FIG. 1

FIG. 2

INVENTOR
CHARLES F. LORENZ

BY
J. Abbott
ATTORNEY

UNITED STATES PATENT OFFICE.

CHARLES FREDERICK LORENZ, OF EAST ORANGE, NEW JERSEY, ASSIGNOR TO WEST-
INGHOUSE LAMP COMPANY, A CORPORATION OF PENNSYLVANIA.

LUMINOUS ELECTRODE DISCHARGE LAMP.

Application filed March 14, 1923. Serial No. 624,915.

This invention relates to electric incandescent lamps and more particularly to lamps which are operated by an electrical discharge.

5 An object of my invention is the provision of a lamp in which substantially all of the energy is converted from the electrical state into radiation.

Another object of my invention is to provide a lamp of the electrical discharge type and employing electrodes in which the heat generated in the gaseous path of the discharge and the heat of all but one of the electrodes, is prevented from loss by radiation 15 and convection.

Another object of my invention is to provide a lamp having its electrodes so disposed and shaped as to effectively transform all of the electrical energy put into the lamp from 20 that state into radiation.

A further object of my invention is the provision of an electric incandescent lamp in which the light-giving bodies are of such form as to give a good life-temperature performance.

25 Other objects of the invention will be apparent from a reading of the following description.

In electric lamps employing, as the light-giving source, a filament, formed of straight or coiled wire, considerable loss of electrical energy which has been converted into radiation is experienced by convection and conduction. In lamps which employ an arc 30 or an electrical discharge for illuminating purposes, considerable loss is occasioned through convection and conduction of the heat generated in the gaseous path of the discharge. It is obvious that, if this heat 35 could be conserved and utilized to aid in bringing the illuminant to the temperature at which light is given off, saving might be effected in the actual energy input of the lamp for a given temperature.

40 It has also been observed that good life with a satisfactory temperature performance cannot be obtained with filaments of small diameter. It is a well known fact that, upon heating a refractory metal to the temperature 45 at which light is obtained, the diameter of the filament slowly diminishes through

vaporization of the material. The smaller the diameter of the filament, the quicker the life of the lamp in which such filament is positioned is terminated.

55

I propose to overcome the above objections and accomplish the objects mentioned above by constructing a lamp having electrodes which are so shaped and disposed with respect to each other that the one electrode is

60

substantially inclosed by, and spaced from, the other electrode or electrodes. An electrical discharge is utilized to bring the electrodes to incandescence. The arrangement 65

of the electrodes and their shape, prevents the loss by radiation and convection of the heat of the inner electrode and also the heat generated in the gaseous path of the discharge.

70

Furthermore, the electrodes, by reason of their massive form, as compared with the filamentary form of the light-giving element of an ordinary incandescent lamp, is not so subject to destruction by vaporization or the development of a "hot-spot", as is a filament, and has a longer life than a filament 75 operated at the same temperature.

Referring to the drawing:

Fig. 1 is a view, partially broken away, in elevation of one embodiment of my invention; and,

80

Fig. 2 is a view of the concentric electrodes, the inner electrode being shown in end elevation and the outer electrode in section.

85

The embodiment of my invention illustrated in the accompanying drawing, may comprise a transparent spherical envelope 3. Disposed within the envelope are electrodes 4 and 5. These electrodes may be arranged centrally with respect to the envelope 3, 90 for a purpose more fully described herein-after.

In order to conserve the energy which is radiated by the inner electrode, I preferably dispose the same within the outer electrode 95 4, the latter being made hollow in order to secure this result. The inner electrode may be spaced a uniform distance from the outer electrode, and in order to increase the surface area thereof, so that its surface area 100 may more nearly equal, in magnitude, the inner surface area of the outer electrode, it

may be corrugated or given any other desired configuration to accomplish the purpose desired.

The inner electrode may be given the form 5 of a sphere which may be hollow or solid. The outer electrode may be similarly formed, it being obvious, however, that, in order to place the inner electrode therein, it is essential that the same be hollow.

10 The electrode 5 may be positioned within the outer electrode 4 by providing an opening 6 in the outer electrode of such size as to permit the passage of electrode 5 therethrough. It is obvious to those skilled in 15 the art that other methods or structures may be employed for accomplishing this end.

For positioning and supporting the inner electrode within the outer electrode, the electrodes 4 and 5 may be connected to supports 20 7 and 8, respectively. These supports may serve as leading-in wires for the current supplied to the lamp. A stem 9 having a press 10 may be provided, as in usual lamp design. If desired, auxiliary supports (not 25 shown) may be provided, in order to maintain the electrodes in the desired adjusted positions.

By placing the inner electrode within the outer electrode and utilizing an electrical 30 discharge to bring the electrodes to a high temperature, the heat generated in the path of discharge is prevented from loss as the outer electrode absorbs substantially all of such energy. In addition to this, the heat 35 which is radiated by the inner electrode and across the space between the inner electrode and the outer electrode is also absorbed by the latter electrode.

If it is desired to utilize the lamp for 40 flood lighting or projection purposes, much of the energy liberated by the electrodes may be effectively conserved by providing the inner surface of the envelope 3 with a mirror 11 of any suitable material, such as 45 silver or the like. A clear space 12, centrally disposed with respect to the envelope 3, may be provided in order to permit the light to emerge from the lamp. By this arrangement, radiant energy, which is not in 50 the form of light, may be reflected back upon the electrode to assist in heating the same. In order to accomplish this latter object, it is desirable to have the electrodes disposed centrally within the spherical envelope 55 3.

The envelope may be filled with any desired gaseous atmosphere which is capable of sustaining an electric discharge. The gas used should be of such nature as to be 60 inert with respect to the electrodes. A suitable gas may consist of argon, neon, helium, nitrogen and the like, or mixtures of gases. The pressure of the gas is preferably less than atmospheric, for example, it may be of 65 the order of 600 mms. of mercury.

In the operation of the lamp, a current, at a sufficient potential, is passed through the leading-in wires 7 and 8. An electric discharge is thus caused to occur between the electrodes 4 and 5, which, in turn, causes the electrodes to become highly heated. The heat which is generated in the discharge path is absorbed by the outer electrode 4 and is thus prevented from loss through 70 radiation and convection. At the same time, the heat which is radiating from the inner electrode 5 is also absorbed by the outer electrode and the gas also helps to transfer heat from the inner to the outer electrode. The outer electrode is, thereby brought to 75 a high degree of incandescence, thus furnishing an efficient light source, through the conversion or transformation of practically 80 all of the energy from the electrical state into radiation.

Many modifications will suggest themselves, but those are contemplated which fall within the spirit of my invention as defined by the appended claims.

What is claimed is:

1. An electric incandescent lamp comprising an envelope containing an electrical discharge-sustaining atmosphere, an electrode within said envelope and at least one other electrode disposed around said first mentioned electrode and spaced uniformly therefrom so as to absorb substantially all of the heat radiated from said first mentioned electrode and reach a state of incandescence to constitute a light source.

2. An electric incandescent lamp comprising an envelope containing an electrical discharge-sustaining atmosphere, a light source comprising a plurality of electrodes disposed within said envelope, at least one of said electrodes being composed of a hollow substantially spherical body of a refractory material, enclosing the said discharge and adapted to be heated to constitute a light source.

3. An electrical incandescent lamp comprising an envelope containing an electrical discharge-sustaining atmosphere and a pair of electrodes, one of said electrodes consisting of a hollow substantially spherical body and the other electrode being disposed within said body and spaced substantially uniformly therefrom.

4. An electric incandescent lamp comprising an envelope containing an electrical discharge-sustaining atmosphere and a plurality of substantially spherical electrodes, one of said electrodes being hollow and another being concentrically disposed within the former electrode and spaced therefrom.

5. An electric incandescent lamp comprising an envelope containing an electrical discharge-sustaining atmosphere and a plurality of electrodes, one of said electrodes consisting of a hollow body having an opening

in one side thereof and the other electrode consisting of a body having its greatest dimension equal to the corresponding dimension of said opening, said second electrode being arranged within the other electrode and uniformly spaced therefrom.

6. In an electrical incandescent lamp, a pair of electrodes, one substantially entirely enclosed within the other and spaced a uniform distance therefrom over substantially its entire area whereby a uniform discharge path is produced between said electrodes.

7. In an incandescent electric lamp of the discharge type, means for conserving the heat generated in the gaseous path of the discharge comprising a refractory shell substantially entirely enclosing said discharge,

adapted to absorb the heat therefrom and constituting the sole light source of said lamp.

8. In an electric incandescent lamp of the discharge type employing a pair of electrodes, means for producing a source of light by conserving the heat generated in the gaseous discharge path and also the heat radiated by one of the electrodes consisting in enclosing said discharge and one of said electrodes within the other electrode to bring the enclosing electrode to a state of incandescence.

In testimony whereof, I have hereunto subscribed my name this 13th day of March, 1923.

CHARLES FREDERICK LORENZ.
